SHEET PILING APPARATUS

Robert Joseph Kovatch, Baltimore, Md., assignor
to Bethlehem Steel Company, a corporation of
Pennsylvania

Original application July 16, 1949, Serial No.
105,225. Divided and this application October
24, 1950, Serial No. 191,758

7 Claims. (Cl. 214—6)

1

My invention relates broadly to a machine for automatically piling sheets to form stacks, and is more particularly adapted for use in the manufacture of tin plate, although it can be used for stacking sheets of other material equally as well where a similar purpose is desired, and this application is a division of my copending application Serial No. 105,225, filed July 16, 1949, for Sheet Balancer and Guide.

In the manufacture of tin plate after it is rolled and cut into sheets of sizes usually 20" x 28" they are passed through an electric cathodic cleaner. The uncoated sheets are then advanced therefrom by a pair of over-shot conveyors which drop the sheets onto a table which feed them in two rows into a tin pot and then to a catcher for receiving the coated sheets as they come from the tin pot, a cooling and washing table, a branner or polishing machine, and finally to a piler to form stacks of the tin plate.

In my invention the sheets of tin plate after they come out of the branner are fed by a conveyor to an inclined trough down which they slide by gravity onto a pair of sheet balancers which drop the sheets into the sheet piler box. The balancers drop the sheets flat and straight in the piler box so that one edge will not drop on the stack first, avoiding kinks, cobbles, bending or scratching the surfaces of sheets in the pile. An adjustable weight is provided for each balancer, so that any weight of sheet can be dropped onto the pile at the correct time.

One of the objects of my invention is to provide a sheet balancer and guide that will receive a sheet as it leaves a conveyor or the like and guide the sheet to its proper position to pile the sheets in a sheet piler box and drop each sheet in such a manner so as to prevent scratching of the previously fed sheet due to the rough shear edge dragging as the sheets fall.

A further object of my invention relates to the screw adjusting weight on each sheet balancer that can be adjusted to make the balancers trip at the right time for any weight of sheet.

Other objects and advantages of my invention will hereinafter appear.

Referring now to the accompanying one sheet of drawings which form a part of this specification and on which like characters of reference indicate like parts.

Figure 1 is a perspective view showing the manner of feeding the sheets to the tin plate piler box illustrating one form of sheet balancers I may use, and

Figure 2 illustrates the operation of a slightly

2

modified form of a pair of sheet balancers and guides for depositing a sheet on the pile of sheets in the tin plate piler box.

Referring now to the various characters of reference on the drawings the numeral 1 indicates the sheets of tin plate after they come out of the branner or polishing machine, and they are then fed by means of rollers 2 to an inclined trough 3, down which they slide by gravity onto the sheet balancers 4.

As indicated in Fig. 1 two spaced piling boxes 5 and 6 are shown of similar construction which are connected together by means of a plate structure as at 7. The inclined trough 3 has a supporting base 8, which is pivoted to the plate structure 7 as at 9. The supporting base 8 has an arc shaped arm 10 attached thereto and is provided with a set bolt 11, which extends through an arc shaped slot 12 in the plate structure 7 and provided with an adjustable hand wheel nut 13. As illustrated in Fig. 1 the sheet 1 is being discharged into the front piling box 5 to form a pile or stack 14. After the stack 14 has been built up to the desired height the hand wheel nut 13 is unscrewed slightly and the back end of the inclined trough 3 is tilted downwardly manually to allow the sheets 1 to be discharged into the rear piling box 6, the hand wheel nut 13 is then tightened to clamp the inclined trough 3 in this position. In this manner while the stack 14 in the forward piling box 5 is being removed the stack 14 in the rear piling box 6 is being formed, in this manner the trough 3 is readjusted after each stack 14 is formed and the operation is continuous.

The piling boxes 5 and 6 each have a base 15 and side plates 16 and 17, the latter of which is preferably hinged. The upper portions of the side plates 16 and 17 are inclined outwardly as at 18 to form guides for the sheets 1 and are provided with journal bearings 19 for the axles 20 of the sheet balancers 4.

The pair of sheet balancers 4 are of substantially rectangular outline in top plan and are each formed of rod members, the outer rod 21 having a greater cross sectional area than the rod which forms the ends 22 and the inner rod member 23, these preferably being formed in one piece and the ends welded as at 24 to the outer rod 21. The inner portions of the ends 22 are formed arc shaped as at 25 to prevent the advancing edges of the sheets 1 from engaging the same. Attached to one end of each sheet balancer 4 is a substantially U-shaped bracket arm 26 each having the end of one leg welded as

at 27 to one of ends 22 and the other leg welded as at 28 to the outer rod 21. The central portion of the U-shaped arm is formed straight and screw-threaded as at 29 to receive an adjustable threaded counter weight 30, which is more securely held in position by means of nuts 31.

Normally the counter weights 30 hold the ends 22 and the inner rods 23 in the raised position with the outer rods 21 engaging the stops 32 which are secured to and extend upwardly from each of the inclined upper portions 18 of the side plates 16 and 17.

Each piling box 5 and 6 is provided with a swinging door 33 at the outer end having buffer plates 34 on the inner side for limiting the forward movement of the sheets when they are discharged into the piling box. Each door is supported by a standard 35 in which is mounted a swinging arm 36, the outer end having a threaded bolt 37 mounted therein and adapted for adjustment by means of a hand wheel nut 38 and a lock nut 39. The lower end of the threaded bolt 37 is provided with a cross bar 40 with its end portions connected by means of chains 41 to the swinging door 33.

In operation after the sheet leaves the feed rollers 2 it is fed by gravity from the inclined trough 3 and engages the inner rod member 23 of the two sheet balancers 4 and the weight of the sheet will tilt the balancers, and the sheet will be discharged into the piling box as indicated in dotted lines in Fig. 2.

In Fig. 2, I have illustrated a slight modification in which the threaded bracket arm 42 for the adjustable counter weight 43 and clamping nut 44 is shown substantially L-shaped, but the operation of the balancers 4 are substantially the same as that described for Fig. 1.

After each stack 14 is completed the door 33 is swung out of position and a truck having a lower shelf-like projection is adapted to extend under the stack and convey it to the assorting room where they are placed upon well lighted tables for inspection, all of which is well known in this art.

Although I have shown and described my invention in considerable detail, I do not wish to be limited to the exact construction shown and described, but may use such substitutions, modifications or equivalents thereof, as are embraced within the scope of my invention, or as pointed out in the claims.

I claim:

1. A sheet piling apparatus for tin plate or the like, comprising a conveyor for receiving the sheets from a polishing and cleaning machine from which they are discharged in sequence onto an inclined trough for receiving the sheets from the conveyor and feed them by gravity into a piling box, outwardly inclined guide plates for the sheets at the top of the opposite side walls of the box, a sheet balancer journaled in bearings attached to the top of each of the opposite side walls of the piling box, said sheet balancers each having an inner horizontally disposed rod adapted to initially support the sheets at the top of the piling box and to yield under the weight of the sheet and drop the sheet into the piling box.

2. A sheet piling apparatus for tin plate or the like, comprising a conveyor for receiving the sheets from the polishing and cleaning machine from which they are discharged in sequence, an inclined trough for receiving the sheets from the conveyor and feed them into a piling box, out-

wardly inclined guide plates for the sheets at the top of the opposite side walls of the piling box formed integral therewith, a sheet balancer journaled in bearings attached to each of the inclined guide plates for the sheets at the opposite side walls of the piling box, said sheet balancers each having an inner horizontally disposed rod member adapted to engage and initially support the sheets at the top of the piling box and adapted to yield under the weight of the sheet and drop the sheet into the piling box, and adjustable means on each of the sheet balancers to allow sheets of different weights to be dropped into the piling box at the correct time.

3. A sheet piling apparatus for tin plate or the like, comprising a conveyor for receiving the sheets from a polishing and cleaning machine from which they are discharged in sequence, a pair of piling boxes disposed adjacent to the conveyor, a trough for receiving the sheets from the conveyor, means for inclining the trough so that the sheets received thereon will slide either into one piling box or the other, outwardly inclining guide plates for the sheets at the top of the opposite side walls of each of the piling boxes, a sheet balancer having axles journaled in bearings attached to each of the inclined guide plates for the sheets at the opposite side walls of each of the piling boxes, said sheet balancers each having an inner horizontally disposed rod member adapted to normally engage and initially support the sheets at the top of the piling boxes and adapted to yield under the weight of the sheet and drop the sheets into the piling boxes, and adjustable means on each of the sheet balancers to allow sheets of different weights to be dropped into the piling box at the correct time.

4. A piling apparatus for sheet material, comprising a conveyor for receiving the sheets from which they are discharged in sequence, an inclined trough for receiving the sheets from the conveyor and feed them into a piling box, outwardly inclined guide plates for the sheets at the top of the opposite side walls of the piling box formed integral therewith, a sheet balancer having axle extensions journaled in bearings attached to each of the inclined guide plates for the sheets at the opposite side walls of the piling box, said sheet balancer having an outer horizontally disposed rod member and an inner horizontally disposed member, end rod members connecting the ends of the inner and outer horizontally disposed rods, said inner horizontally disposed rod member of each sheet balancer adapted to engage and initially support the opposite sides of the sheet at the top of the piling box and adapted to yield under the weight of the sheet and drop the sheet into the piling box, adjustable means on each of the sheet balancers to allow sheets of different weights to be dropped into the piling box at the desired time and means for limiting the movement of the sheet balancers.

5. A piling apparatus for sheet material, comprising a conveyor for receiving the sheets from which they are discharged in sequence, an inclined trough for receiving the sheets from the conveyor and feed them one at a time into a piling box, outwardly inclined guide plates for the sheets at the top of the opposite side walls of the piling box formed integral therewith, a pair of journal bearings attached to the outer surface of each outwardly inclined guide plates, a sheet balancer having an outer horizontally

disposed rod member and an inner horizontally disposed member, end rod members connecting the ends of the inner and outer horizontally disposed rods, an axle extension extending from each of the end rod members journaled in the bearings mounted on the inclined guide plates, said inner horizontally disposed rod members of each sheet balancer adapted to engage and initially support the opposite sides of the sheet at the top of the piling box and adapted to yield under the weight of the sheet and drop the sheet into the piling box, a threaded rod extension connected to one end of each sheet balancer, a weight having a threaded opening for engaging each threaded rod adapted to be adjusted to allow sheets of different weights to be dropped into the piling box at the desired time, and a stop for limiting the movement of each sheet balancer.

6. A piling apparatus for sheet material, comprising a conveyor for receiving the sheets from which they are discharged in sequence, an inclined trough for receiving the sheets from the conveyor and feed them by gravity in succession to a piling box, outwardly inclined guide plates for the sheets at the top of the opposite side walls of the piling box formed integral therewith, a pair of journal bearings attached to the outer surface of each outwardly inclined guide plate, a sheet balancer attached to each outwardly inclined guide plate each having an outer horizontally disposed rod member and an inner horizontally disposed rod member, end rod members connecting the ends of the inner and outer horizontally disposed rods and an axle extension extending from each of the end rod members journaled in the bearings mounted on the inclined guide plates, said inner horizontally disposed rod members of each sheet balancer adapted to engage and initially support the opposite sides of the sheet at the top of the piling

box and adapted to yield under the weight of the sheet and drop the sheet into the piling box.

7. A sheet piling apparatus for tin plate or the like, comprising a conveyor for receiving the sheets from a polishing and cleaning machine from which they are discharged in sequence, a pair of piling boxes disposed adjacent to the conveyor, a trough mounted between the pair of piling boxes for receiving the sheets from the conveyor, means for inclining the trough so that the sheets received from the conveyor will slide either into one piling box or the other, outwardly inclined guide plates for the sheets at the top of the opposite side walls of each of the piling boxes, a sheet balancer having axle extensions journaled in bearings attached to each of the inclined guide plates for the sheets at the opposite side walls of each of the piling boxes, said sheet balancers each having an inner horizontally disposed rod member adapted to normally engage and initially support the sheets at the top of the piling boxes and adapted to yield under the weight of the sheet and drop the sheets into the piling boxes, means for automatically returning the sheet balancers to their normal position after the sheet is dropped into the piling box, and adjustable means on each of the sheet balancers to allow sheets of different weights to be dropped into the piling boxes at the desired time.
